UNITED STATES PATENT OFFICE.

ANNIBALE GASPERETTI AND CARLO DALBONI, OF NEW YORK, N. Y.

MUSIC-LEAF TURNER.

1,169,144.

Specification of Letters Patent.

Patented Jan. 25, 1916.

Application filed December 4, 1914. Serial No. 875,457.

To all whom it may concern:

Be it known that we, ANNIBALE GASPERETTI, a citizen of the United States, and CARLO DALBONI, a subject of the King of Italy, residing at New York, borough of Manhattan, in the county and State of New York, have invented certain new and useful Improvements in Music-Leaf Turners, of which the following is a specification.

- 10 Our invention relates to improvements in devices for turning sheet music, especially in the form of books, consisting of a number of leaves bound together with or without covers; and in its preferred embodiment, 15 it comprises suitable mechanism for engaging the sheets or leaves, operable at will to turn the sheets in succession till the end of the musical composition upon the face of the sheets is reached.
- 20 The primary object of our invention is to provide a device of the kind mentioned, which will afford positive and certain engagement of the mechanism with the sheets; so that the sheets can be turned over one 25 after another in a manner that is both quick and infallible.

The above and other objects and advantages of our invention will appear from the following description taken in connection 30 with the accompanying drawings, which show a preferred form of our invention; the same characters of reference being used to indicate the same parts throughout the several views.

35 On said drawings Figure 1 is an elevation showing our invention attached to a stand for supporting sheet music commonly used by violinists. Fig. 2 is a front elevation of the mechanism, comprising our invention. 40 Fig. 3 is a top plan of the same. Fig. 4 is a top view, partly in section, showing the operative position of certain parts. Fig. 5 is a vertical section taken centrally through the mechanism comprising our invention.

45 Fig. 6 is a side elevation, showing the parts comprising our invention in one position. Fig. 7 is a view similar to Fig. 6, showing the same parts in the position they occupy at the end of the sheet turning operation; 50 and Fig. 8 is a perspective view of a detail, illustrating the manner in which the mechanism we employ takes hold of the sheets of music to turn them over.

In the particular description of the drawings, we use the numeral 1 to indicate a stand for supporting music of the kind com-

monly used by violinists. This stand comprises a post consisting of a number of tubular sections which telescope within one another and are extensible so that the stand can be collapsed to be packed in the musician's case or set up at will. This stand carries at its top a music rest 2 and has legs at the bottom which can be folded up against the lowermost section in the usual way. When the stand is being used, the various parts are held in fixed relation with each other by means of suitable binding screws.

Further description of the stand is not believed to be necessary, as the parts are plainly shown in Fig. 1 and well known to those skilled in the art. Furthermore, various kinds of stands may be used in connection with our invention and the one shown on the drawings is intended merely as a conventional illustration to show one method of applying our invention. Obviously, our music turning device may be employed in combination with the music rest of a piano or any other instrument. The rest 2 may also be of any suitable type, consisting of parts rigid with each other; or adapted to be folded together, so as to carry in convenient position, inclining slightly backward, the sheets of music 3. The central member of the rest is shown at 4, and it may have pivotally connected to the bottom thereof two angle bars 5, forming a shelf to engage the bottom edges of the sheets 3. Each of the sheets 3 will have on the face thereof, which is the upper face, when the sheet is turned over to the right of the central frame member 4, an engageable body in the form of a flap 6 having a pointed end 7 and an opening 8. These flaps may be made of celluloid, parchment, paper or any other suitable material, and are preferably attached by pasting them along their upper edges to the sheets 3 near the lower corners of the sheets, in such position that the points 7 will extend toward the inner or bound edges of the sheets. These flaps are free along all the edges except the upper edges, and as they are made of thin, but somewhat stiff material, they will not appreciably increase the thickness of the sheets to which they are attached. When the book of music is closed, the flaps will be pressed tightly against faces of the sheets; but when the book is opened, the pointed end 7 will extend away from the faces of the sheets to a slight

extent; being bent so as to give it a sufficient permanent set for this purpose. In order to turn the sheets, the flaps are engaged by suitable means carried by a pivot arm 9, which revolves in a plane substantially normal to the rest 2, as we shall now set forth.

To the upper end of the uppermost tubular section of the stand 1, we attach a sleeve 10 in which is received the lower end of a bent 10 shank 11. The upper end of the shank passes into a socket formed by a plate 12, secured to the back of an angle plate 13. This angle plate supports the music rest 2 and the back thereof may have a groove 14 to receive the lower end of the frame member 4. The back of this angle plate 13 may also be slotted at the middle of the groove 14 and the bottom of the frame member 4 may have a bolt extending therefrom to pass into the 20 slot and be engaged by a binding nut to secure the member 4 and the angle plate 13 together. This bolt and binding nut are shown at 15, and it will be seen that when the rest 2 is secured to the angle plate, that 25 the back and bottom of this angle plate will be substantially parallel to the back and bottom respectively of the angle bars 5.

To the lower side of the bottom or front portion of the angle plate 13, we secure a 30 casing 16, providing a bearing for a spindle 17. This spindle also passes through the angle plate 13, and is encircled by means of a coil spring 18, secured thereto into the inside casing 16. The spindle 17 also carries 35 inside the casing 16 and rigid thereon a drum 19, which has fixed thereto one end of an operating cord or chain 20. This cord or chain 20 passes through an opening in the casing 16 and over a grooved guide wheel 21, 40 carried by the sleeve 10, into the tubular sections making up the post of the stand 1. The pulley 21 is suitably journaled in projections carried by the sleeve 10, and both this sleeve and the lower end of the bent 45 shank 11 will be shaped so as to give free passage to the cord or chain 20, as clearly shown in Fig. 5. The upper end of the spindle 17 carries above the front portion of the angle plate 13 a head 22. This head 22 50 has a pair of lugs 23, between which is pivotally mounted a short arm 24. This arm has a collar thereon at its outer end, indicated at 25, and the outer face of this collar carries a boss which fits into an aperture 55 in an end of the arm 9, above mentioned; a binding screw 26 being used to secure the arm 9 and short arm 24 together. This arm 9 carries a pivoted lever 27, mounted thereon, adjacent the screw 26, and carrying at its 60 outer extremity an upturned pin 28. Preferably the arm 27 is provided with ears at its pivoted end, which receive the arm 9 between them; (see Figs. 2 and 5); and the arm 9 may be recessed around the pivot pin 65 to receive a coil spring shown at 27' in Fig.

4, which normally tends to force the lever 27 and arm 9 apart.

At its outer end, the lever 27 is bent forward adjacent the pin 28, forming a lateral extension 29, upon which is pivotally mounted a locking dog 30. As shown in Fig. 8, this locking dog 30 has a curved apertured end 31, and the opposite end is heavier than the end 31, so that normally this dog will be in vertical position. The adjacent end 75 of the arm 9 carries a projection or finger 32 on the top thereof, located above the level of the pivot of the locking dog 30, and extending beyond the end of the arm 9, which arm will terminate short of the dog 30 when the arm and lever are forced together, as will be presently set forth. Consequently, when the arm and lever come together, as shown in Figs. 2 and 3, the finger 32 will strike the up-curved end 31 of the dog 85 and throw it into substantially horizontal position.

The outer end of the extension 29 of the lever 27 is bent parallel to the lever 27 toward the pivot thereof to provide a projection 33, adapted to be engaged by a locking bolt 34, slidably mounted in a bore in the outer end of the arm 9. This bolt 34 is normally forced outward by a spring at the inner end of the bore, as shown in Fig. 4, and 95 it has a pin 35 projecting through a slot 36 at the top of the arm 9, to limit the outward movement. Hence, when the lever 27 and arm 9 are forced together, they will be locked against the compression of the spring 27', and will remain locked until released.

In the practice of our invention, the arm 9 and lever 27 come together when the head 22 revolves to the right, referring to Figs. 2, 3 and 4, and are unlocked when they revolve 105 in the opposite direction. For this purpose, we provide the angle bar 5 at the left with a projection 37 in position to engage the pin 35 when the arm and lever swing over to the left, and force the pin toward the inner end of the arm 9; whereby the bolt 34 will be drawn and the lever 27 released. Of course, the slot in the groove 14 in the back of the angle plate 13 which receives the locking bolt 15 terminates at such a point that 110 these angle bars will be spaced a sufficient distance from the bottom portion of the angle plate 13 to allow the arm 9 and lever 27 to move below them, and we provide the two angle bars 5 with recesses 5' to avoid 115 interfering with the pin 28, dog 30, and pin 35 when the arm and lever are in either extreme position. The lever 27 is provided with an upstanding lug 38 offset laterally of the lever and located so as to be struck by 120 the outer end of the projection 37 after the same has moved the pin 35 to withdraw the bolt 34; whereby the arm and lever will be separated, even if the spring 27 does not act 125 quickly enough when the lever 27 is released. 130

Referring again to the short arm 24, it will be seen by referring to Figs. 1 and 6 that we provide the head 25 with a projection 39; this projection extending toward the head 22 and being below the body of the arm 24 so as to provide a space or recess. The arm 24 being pivoted to the head 22 so as to swing up and down in a vertical plane; it will be seen that the projection 29 will limit downward movement of the short arm 24 by engaging front or bottom portion of the angle plate 13. We mount on the front portion of this angle plate a curved strip 40 which provides a circular track for the projection 39, and this track 40 extends from right to left and terminates at the left in a beveled end, located a slightly greater distance from the back portion of the angle plate than the spindle 17; reference being had particularly to Figs. 4, 6 and 7. Adjacent the left edge of the back portion of the angle plate, we pivot a bridge piece 41, having a lateral projection 42 resting upon the beveled end of the curved track piece 40. This projection provides a continuation of the surface of the track a slight distance past the beveled end; the front edge of this projection being also beveled, and the rear edge being abrupt. As shown in Fig. 4, the bridge piece 41 is located inward of the edge of the front portion of the angle plate 13, whereby a drop is provided for the projection 39 beyond the lateral projection 42 and the relative thickness of the track piece 40, bridge piece 41 and projection 39 is such that when the projection 39 passes beyond the projection 42 and drops off the same, the top of the projection 39 will be below the projection 42, as shown plainly in Figs. 6 and 7. The bridge piece 41 is pivoted to the plate 13 by means of perforated lugs and a spring head encircling the pivot pin is shown in Fig. 4 to hold the bridge piece down.

To the back portion of the angle plate 13, we pivot a curved resilient finger 43, which is engaged by a spring 44, secured to the front portion of the angle plate so as to hold the finger downward against the front portion of the angle plate between the lateral projection 42 of the bridge piece 41 and the back of the angle plate, as shown in Fig. 6. This finger 43 is lifted by the short arm 24, the top of which may be beveled for this purpose, as shown in Fig. 7. A clamp 45, consisting of spring wire, may be pivoted to the outer end of the right hand angle bar 5 to engage the leaves 3 beyond the flaps 6, this clamp being shaped to press lightly upon the leaves 3 and prevent them from being blown over without interfering with the operation of our invention. The function and utility of our improvement will now be plain. Normally, the spring 18 rotates the shaft 17 to throw the arm 9 and lever 27 to the right, and a pull on the cord 20 will rotate the shaft 17 against the spring 18 to move the arm and lever to the left and turn the sheets.

Suppose, for example, the parts be considered with reference to their position shown in Fig. 4; the lever 27 being urged at its outer end away from the bar 9 by the spring 27' at this time. Since the outer end of the arm 9 and lever 27 are tilted slightly upward, owing to the fact that the rest 2 is inclined to the rear, the action of gravity will assist the spring 27 when the arm and lever are to the right of the spindle 17, and make the moving apart of the arm and lever more certain. The lever 27 will therefore cause the pin 28 to come into contact with the sheet 3 to be turned, at a point inward of the flap 6; the pin 28 entering the recess 5' in the right hand angle bar 5 far enough to permit this action. The continued revolution of the arm 9 to the right forces pin 28 behind the pointed end 7 of the flap 6; and the outer ends of the arm and lever now begin to move toward each other. When the pin 28 reaches the aperture 8, the finger 32 on the arm 9 strikes the curved end 31 of the locking dog 30 and throws it toward the sheet 3. As a result, the opening in the end 31 of the dog receives the upper end of the pin 28 and completes the locking engagement of the dog and pin with the flap 6. Simultaneously, the bolt 34 passes behind the projection 33 and locks the arm and lever together. The pin 28 will always pass behind the flap 6, because it naturally presses against the sheet or leaf to be turned as it slides along the face of the same toward this flap; this condition being clearly indicated in Fig. 4. By making the ends 7 of the flap pointed, the passing of the pin 28 behind the flap can be rendered certain in every case; because this pointed end will normally tend to stick upward from the plane of the sheet at a slight angle. We prefer to curve the pointed ends 7 of the flaps outward by working them with the fingers; so as to give them a slight permanent set away from the page. These ends will, of course, be pressed flat against the pages to which the book is closed; but as fast as each flap is uncovered by turning a sheet the pointed end 7 will assume the necessary outward extending position to obviate every possibility of the turning device failing to engage the sheet in the proper manner. This much of the operation is effected by the spring 18. The cord or chain 20 is now pulled, rotating the spindle 17 to the left. The arm 9 and lever 27 now pull the sheet 3, by means of flap 6, out from under the clamp 45 and turn it over. When the arm and lever have revolved far enough to the left to occupy the position shown in broken lines in Fig. 3, the projection 37 will push

4 back the pin 35 to release the lever 27, and the projection 37 will then engage the lug 38 to coöperate with the spring 27' to separate the arm and lever. As soon as this happens, the finger 32 having moved away from the locking dog 30, the heavier end of the locking dog opposite the curved end 31 drops; thus disengaging the upper end of the pin 28. About this time also, the projection 39 passes beyond the inner edge of the projection 42 of the bridge piece 41; whereby the weight of the arm and lever will cause these two parts to revolve the short arm 24 around its pivotal connection 15 with the head 22, downward far enough to enable the pin 28 to be withdrawn behind the flap 6, and thus release the same. The completion of the turning operation is effected by the top of the short arm 24 engaging the bottom of the curved finger 43, and raising it against the tension of the spring 44, as shown in Fig. 7 to engage the reverse side of the sheet 3 near its bound edge and force it down flat against the cover or sheets 20 that have been turned before it. The upper face of the arm 24 may be beveled for this purpose. The cord or chain 20 is now released and the spring 18 moves the arm 9 and lever 27 to the right again. In returning, the projection 39 passes under the lateral projection 42 of the bridge piece 41; riding easily upward over the beveled end of the track piece 40 to the top of the same, and the operation can be repeated.

35 We prefer to lead the cord or chain 20 down through the tubular sections, making the post of the stand 1, and actuate the same by means of a pedal at the bottom of the stand so as to leave the hands of the musician entirely free. The actuating device in question is shown in Fig. 1, and it is in the form of a bellows comprising a pair of heads 46 connected by a web of sheet rubber or leather 47. On the top of the upper head 45 46 is a plate 48, secured to the head at its ends, but spaced from the head between the ends. The pressure of the foot on this plate will collapse the bellows, as will be readily understood. The head 46 is perforated below the plate 48, and an ordinary flap valve of cloth or any other suitable material may be secured to the head and located between the same and the plate 48, to cover the perforations; these perforations permitting air 50 to pass into and out of the bellows. The flap valve is indicated by the numeral 49.

To the heads 46 we pivot two pairs of links 50; the links of each pair being pivotally connected together, thus providing a 55 double toggle point. To the pivot ends of one pair of links, namely the pair shown at the right, we secure one end of a flexible, tubular casing 51 for the operating cord or chain, and to the pivot ends of the pair 60 of links at the left, we secure a boss having

an aperture to receive a bolt through which the end of the cord or chain 20 is adapted to be fastened. This bolt will carry an adjusting nut 52. It will now be seen that when the musician presses downward with 70 his foot on the plate 48, the links 50 will cause a pull to be exerted on the end of the cord 20 to throw the arm 9 and lever 27 to the left. At this time, the flap 49 lifts and allows the air in the bellows to escape. 75 When, however, the musician moves his foot from the plate 48, thus releasing the bellows, the spring 18 can move the arm and lever to the right. When this action takes place, however, the spring pulls the cord in 80 the other direction, and the cord then actuates the links 50 to distend heads 46 and to restore the bellows to operative position. The flap valve 49 now tends to close, and a partial vacuum thus results inside the bellows. 85 The flap 49 is not perfectly air tight and restricts the inflow of air just enough to prevent the heads 46 from distending too rapidly. Hence, the bellows will act as a sort of cushion to retard the action of the 90 spring 18 and prevent the spring from throwing over the arm 9 and lever 27 to the right too suddenly. Thereby the danger of parts becoming damaged is greatly reduced.

We wish to have it understood that the 95 above disclosure is illustrative only, and we reserve the right to make such changes in the shape, size and arrangement of the parts as fairly fall within the scope and spirit of the appended claims.

100 Having described our invention, what we believe to be new and desire to protect by Letters Patent of the United States is:

1. In a device of the kind described, the combination of a body secured to a sheet to 105 be turned, and having a portion free to move with respect to the sheet, a member adapted to be first passed behind the body, and means movable with reference to said member after said member passes behind 110 the body, to coöperate with said member in the engagement of the body, whereby the body can be actuated to turn the sheet.

115 2. A turning device for sheets of music, comprising an arm movable on a pivot at one end thereof, a lever pivoted on the arm remote from the said end, means for revolving the arm and the lever bodily around the pivot of said arm, means for locking the arm and lever to each other, engaging means carried by the device and actuated to move into operative position with respect to a sheet of music when the arm and the lever come together, means for then revolving the arm and the lever in the opposite direction 120 to turn the sheet, and means for unlocking the arm and the lever from each other and releasing the sheet when the turning has been effected.

125 3. In a device of the kind described, the 130

combination of a music rest, a rotatable head carried by a plate supporting the rest, a short arm connected to the head by a pivot parallel to the plate, an arm connected to 5 the first arm, a lever pivoted to the second arm intermediate the ends of the latter, an upstanding pin and a perforated locking dog on the outer end of the lever, a finger on the second arm to actuate the dog, a bolt 10 for locking the second arm and lever together, means on the rest for releasing the second arm and lever, a track piece having a sloping end on the plate to support the

first arm, a bridge piece providing a drop for the second arm at the end of the track 15 piece, and a finger actuated by the first arm, located adjacent the track piece.

In testimony whereof, we have signed our names to this specification in the presence of two subscribing witnesses, this 21st day of 20 November 1914.

ANNIBALE GASPERETTI.
CARLO DALBONI.
